UNITED STATES PATENT OFFICE.

WALFRID S. EKLUND, OF DONNER, LOUISIANA.

SAFETY MEANS FOR CRANKING INTERNAL-COMBUSTION ENGINES.

1,228,304.

Specification of Letters Patent.

Patented May 29, 1917.

Application filed December 29, 1916. Serial No. 139,711.

To all whom it may concern:

Be it known that I, WALFRID S. EKLUND, a citizen of the United States, residing at Donner, in the parish of Terrebonne and 5 State of Louisiana, have invented certain new and useful Improvements in Safety Means for Cranking Internal-Combustion Engines, and do hereby declare the following to be a full, clear, and exact description 10 of the invention, such as will enable others skilled in the art to which it appertains to make and use the same.

The invention relates to a safety cranking device for internal combustion engines.

15 The object of the present invention is to improve the construction of cranking devices for internal combustion engines and to provide a simple, practical and efficient safety cranking device of strong, durable 20 and inexpensive construction adapted to be applied to various types of engines and cars and equipped with means for automatically disengaging the crank from the engine crank shaft when the engine kicks 25 or reverses.

With these and other objects in view, the invention consists in the construction and novel combination of parts hereinafter 30 fully described, illustrated in the accompanying drawing and pointed out in the claims hereto appended; it being understood that various changes in the form, proportion, size and minor details of construction, within the scope of the claims, 35 may be resorted to without departing from the spirit or sacrificing any of the advantages of the invention.

In the drawing:

40 Figure 1 is a side elevation of a safety cranking device constructed in accordance with this invention.

Fig. 2 is a front view of the same.

Fig. 3 is a rear view of the external ratchet member.

45 Fig. 4 is a sectional view of the external ratchet member.

Fig. 5 is a rear view of the internal ratchet member.

Fig. 6 is a longitudinal sectional view of 50 the same.

Fig. 7 is an elevation of the adjustable disk or plate.

Fig. 8 is a sectional view thereof.

Fig. 9 is an end elevation of the tension 55 spring.

Like numerals of reference designate corresponding parts in the several figures of the drawing.

In the accompanying drawing, in which 60 is illustrated the preferred embodiment of the invention, 1 designates an external ratchet member of cylindrical form provided with four spaced points or engaging portions 1^a which engage with a cross pin 65 in an engine crank shaft (not shown). The outer ratchet member is arranged on an internal ratchet member 2 having four spaced points or portions 2^a which are adapted to disengage the cranking means from the engine crank shaft should the engine kick or reverse. The portions 2^a present inclined edges to the cross pin of the crank, which is yieldably held in engagement with the inclined edges of the portions 2^a by the points 70 or engaging portions 1^a of the external ratchet member, the edges of the points or engaging portions of the external ratchet member being curved, as shown, and adapted 75 to release the said cross pin of the engine crank shaft under an excess of pressure. The internal ratchet member is provided with a reduced portion or sleeve 3^a extending rearwardly from the body of the internal ratchet member which is cylindrical 80 to conform to the configuration of the external ratchet member and provide a bearing for the same.

85 Mounted for rotary movement or adjustment on the sleeve 3^a of the internal ratchet member is an adjusting disk or plate 3 provided with a pair of forwardly projecting lugs 4 adapted to seat in spaced openings 5 of an annular series of openings formed in the flange or shoulder of the exterior ratchet member. The adjustable plate is provided with openings 6 which are adapted to receive one end 7^a of a spring 7 which has its other end 8^a secured in an opening 8 of the reduced portion or sleeve of the internal 95 ratchet member. The tension of the spring is controlled by adjusting the rotary plate on the reduced portion or sleeve and by advancing the disk or plate the tension of the spring is increased and a backward movement of 100 the plate will reduce the tension so that the spring may be adjusted to suit the require- 105

ment. The tension spring 7 performs three different functions. It maintains the external ratchet member and the adjusting plate against the internal ratchet member, and holds the adjusting plate in locking engagement and gives the desired tension between the external and internal ratchet members to enable the cranking device to exert the desired pressure in the ordinary 10 cranking of the engine and to automatically release the crank when the engine kicks or reverses. The reduced cylindrical portion or sleeve of the internal ratchet member forms a crank-receiving opening 9 for the 15 reception of a crank 10 which is secured to the internal ratchet member by a pin 11. The external ratchet member is provided with forwardly projecting lugs 12 arranged diametrically opposite each other at an 20 opening 14 in the external ratchet member and adapted to extend into openings 13 in the internal ratchet member. The openings 13, which are located at diametrically opposite points at opposite sides of the reduced 25 cylindrical portion or sleeve and slightly beyond the same, are of greater width than the lugs 12 to allow for a limited relative rotary movement of the internal and external ratchet members to permit a disengagement 30 of the device from the crank shaft of an internal combustion engine. The lugs 12 and the openings 13 maintain the internal and external ratchet members in proper alignment at all times. The openings 13 are 35 formed in the flange or web portion 5^a of the internal ratchet member. The adjusting plate is provided with a rearwardly projecting arm or portion 15 which is adapted to be grasped or otherwise held to facilitate 40 the adjustment of the spring. The internal and external ratchets may have either two or four points.

While cranking the engine the pressure is exerted on the cross pin of the engine 45 crank shaft, which cross pin rests against the inclined edges of the internal ratchet. The cross pin is held in such engagement with the internal ratchet member by the hook shaped points or portions of the external ratchet 50 member. Should the engine kick or reverse the excessive pressure exerted on the cross pin causes the external ratchet member 1 to revolve and release the cross pin. This rotary movement is against the action of the 55 tension spring which yields under the excessive pressure and permits the cross pin to become disengaged from the device through the action of the inclined edges of the points or portions of the internal ratchet member.

60 What is claimed is:

1. A safety cranking device for internal combustion engines comprising an internal ratchet member provided with engaging portions to receive the cross pin of a crank shaft of an internal combustion engine, an

outer ratchet member provided with engaging portions for holding the cross pin in engagement with the engaging portions of the internal ratchet member, and a spring yieldably connecting the inner and outer ratchet members and adapted to permit the outer ratchet member to yield under an excess of pressure for releasing the cross pin. 70

2. A safety cranking device for internal combustion engines comprising an internal ratchet member of substantially cylindrical form provided with engaging portions having inclined edges adapted to receive the cross pin of a crank shaft of an internal combustion engine, an outer substantially cylindrical ratchet member provided with approximately hook-shaped engaging portions for holding the cross pin in engagement with the said inclined edges, and a spring yieldably connecting the inner and outer ratchet members and adapted to permit the outer ratchet member to yield under an excess of pressure for releasing the cross pin. 80

3. A safety cranking device for internal combustion engines comprising an internal ratchet member of substantially cylindrical form provided with engaging portions having inclined edges adapted to receive the cross pin of a crank shaft of an internal combustion engine, an outer substantially cylindrical ratchet member provided with approximately hook-shaped engaging portions for holding the cross pin in engagement with the said inclined edges, a rotary adjusting plate mounted on the inner ratchet 90 member and provided with means for adjustably engaging the outer ratchet member, and a spring connected with the inner member and the plate. 95

4. A safety cranking device for internal combustion engines comprising an internal ratchet member having engaging portions, an outer ratchet member mounted for rotary movement on the inner ratchet member and provided with engaging portions for holding a crank shaft in engagement with the internal ratchet member, said external ratchet member being provided with an annular series of openings, an adjusting plate mounted for rotary adjustment on the internal ratchet member and provided with lugs for engaging the openings of the external ratchet member, and a coiled spring disposed on the internal ratchet member and having its terminals connected with the 110 same and with the adjusting plate. 115

5. A safety cranking device for internal combustion engines including an internal ratchet member having engaging portions and provided with a reduced cylindrical portion or sleeve having means for securing a crank to it, said internal ratchet member being provided with openings, an external ratchet member having engaging points and mounted for rotary movement on the in- 125 130

ternal ratchet member and provided with lugs extending into the said openings and limiting such rotary movement, and a spring connected with the internal and external 5 ratchet members.

6. A safety cranking device for internal combustion engines including an inner ratchet member having a reduced portion or sleeve and provided with an opening, an 10 external ratchet member mounted for rotary movement on the internal ratchet member and having a lug for engaging the said opening and provided with spaced openings, an adjusting plate also mounted for rotary 15 movement on the internal ratchet member and provided with a lug or projection for engaging the openings of the external

ratchet member, and a coiled spring disposed on the internal ratchet member and connected with the same and with the adjusting 20 plate and maintaining the adjusting plate in interlocked relation with the external ratchet member and retaining the lug of the latter in the opening of the internal ratchet member, said spring also yieldably maintaining the internal and external ratchet members in engagement with the crank shaft of an engine and permitting disengagement under excessive pressure. 25
